J. SCHIFFNER

RAILWAY GRADE CROSSING GATE

Filed Jan. 7, 1925

Patented Apr. 28, 1925.

1,535,548

UNITED STATES PATENT OFFICE.

JOSEPH SCHIFTNER, OF LA GLORIA, CUBA

RAILWAY-GRADE-CROSSING GATE.

Application filed January 7, 1925. Serial No. 961.

To all whom it may concern:

Be it known that I, JOSEPH SCHIFTNER, a citizen of the United States, residing at La Gloria, in the Province of Camaguey, Cuba, have invented certain new and useful ⁴⁵ Improvements in a Railway-Grade-Crossing Gate, of which the following is a specification.

This invention relates to gates for railway grade crossings and has for its primary ¹⁰ object the provision of such a gate that is moved to open and closed position in an entirely automatic manner and without requiring the attention of a gateman.

¹⁵ A further object of the invention is to provide a gate for railway grade crossings wherein the same is mounted for vertical swinging movement upon the horizontal pivot and wherein the nature of the same is ²⁰ to assume at all times a closed position, means being provided for normally maintaining the gate in an open position and means being provided at remote points from opposite sides of the grade crossings operable ²⁵ by the train passing over the tracks to release the gate from its open position whereby the same will automatically drop to a closed position.

³⁰ A further object of the invention is to provide means adjacent the grade crossing operable by the movement of the car over the tracks to throw the same to open position.

³⁵ A further and important object is to provide a device of this character that is of relatively cheap and simple construction and wherein there is little liability of the working parts becoming out of order and wherein the same will operate efficiently under all conditions.

⁴⁰ With the foregoing and other objects in view as the nature of the invention will be better understood, the same comprises the novel form, combination and arrangement of parts hereinafter more fully described shown in the accompanying drawings and ⁴⁵ claims:

In the drawing wherein like reference characters indicate corresponding parts throughout the several views:

⁵⁰ Figure 1 is a side elevational view of my improved railway grade crossing gate and its associate mechanism, the gate being shown in both open and closed position indicated by full and dotted lines respectively.

⁵⁵ Figure 2 is a diagrammatic sectional view of the different structural devices comprised

in the present invention, the same being of an electrical nature and being shown as electrically connected, and

Figure 3 is a detail vertical sectional view ⁶⁰ taken approximately on the line 3-3 of Figure 1 for more clearly disclosing the train operated means for throwing the gate to an open position.

Now having particular reference to the ⁶⁵ drawing, 5 indicates generally a track way that is traversed by highway 6, traffic across which is to be stopped through the medium of my improved crossing gate whenever a train approaches said highway from either ⁷⁰ side thereof.

My invention per se constitutes the provision of a vertically disposed standard 7 located at one side of the highway 6 and to which is pivotally secured by a horizontal ⁷⁵ pivot 8 a gate 9 of the bar or pole type, it being noted that the pivotal connection is adjacent one end of the gate in order that the tendency of the same is to normally maintain a closed position as disclosed by the ⁸⁰ dotted lines in Figure 1.

It will be obvious that if desired there may be provided a gate upon opposite sides of the track way as well as other mechanisms associated therewith to facilitate the opening ⁸⁵ or closing of the same. However, a description of the gate and associated mechanisms upon one side of the track way will suffice.

The gate 9 is maintained in a raised full ⁹⁰ line position shown in Figure 1 through the medium of an electrically controlled latch mechanism that constitutes the provision of a sliding latch bolt keeper 11 formed at the inner end of the gate 9 and within ⁹⁵ which is slidable a latch bolt 12 normally projected outwardly to the position shown in Figures 1 and 2 through the medium of the coil spring 14, it being noted that the forward end of this latch bolt is beveled as at ¹⁰⁰ 13 for the purpose presently to be described. Adjacent the gate supporting standard 7 is a metallic casing 15, the top wall of which is formed with an inclined cylindrical pocket ¹⁰⁵ 16 for the reception of an electromagnet 17. The armature 18 of which is normally projected forwardly thereof through the medium of a heavy expansible spring 19, it being obvious that as the gate 9 is moved to open position the latch bolt 12 will engage said ¹¹⁰ armature and be moved inwardly by contact therewith. The spring 14 will return the

105

latch bolt to the position shown in Figures 1 and 2 and by the engagment of the latch bolt with said armature the gate will be maintained in open position.

5 At points remote from opposite sides of the highway 6 are electrical switch mechanisms designated respectively A and B. Each of these switch mechanisms comprises a metallic casing 20 within which is a stationary contact 21 and a sliding contact 22. The sliding contact is carried by a rod 23 that projects outwardly of the casing and which is pivotally connected at its forward end as at 24 to the lower end of a vertical 10 rock bar 25 carried by a suitable frame 26 disposed adjacent the outer side of one of the rails of the track way 5. This rock bar 25 is maintained in normal vertical position through the medium of a pair of coil springs 27-27 that are secured at their opposite ends respectively to the rock bar and to the frame 26.

The stationary contact 21 of the switch mechanisms are electrically connected to certain poles of storage batteries C and C'. The other poles of these batteries being electrically connected as at a and a' to one contact of the electro-magnet 17, the other contact of this electro-magnet being electrically connected to the sliding contact 22-22 of the switch mechanism through the medium of wires b and b'.

The upper ends of the rock bars 25-25 project slightly above the tread of the adjacent rail engaged by the wheels of the train passing over the highway. It being obvious that the train moving in either direction will engage one of the rock bars for completing the circuit between the storage battery and electro-magnet 17 whereupon the armature will be retracted and when disengaged from the latch bolt 13 the gate 9 will swing downwardly to closed position under its own weight.

45 At the opposite side of the highway 6 from the standard 7 is a vertically disposed hollow post 24' through which is slidably a rod 25' that projects through the upper end of the post and upon which is adapted to rest the gate 9. The lower end of this member 25' engages upon one end of a transversely arranged rock bar 26' that is pivoted at 27' to a casing 28 disposed along the outer side of the adjacent rail of the 50 track way as clearly shown in Figure 3.

Disposed for vertical sliding movement within the casing 28 is a pin 29 that extends upwardly above the tread of the rail to be engaged by the wheels of the car passing over the track way. The lower end of this 60 pin rests upon the adjacent end of the rock bar 26' and it will be obvious that as the wheels of the car engage said pin the rock bar 26' will be actuated for forcing upwardly the member 25' and due to the quick 65 action of the same the gate 9 will be thrown to open position and will be maintained in open position through the medium of the latch mechanism hereinbefore described.

The foregoing description when considered in conjunction with the accompanying drawing, it will be apparent that I have provided a highly novel and efficient railway grade crossing gate that will be moved to open and closed position in an entirely 70 automatic manner.

Minor changes may be made in the invention without departing from the spirit of the invention and scope of the appended 80 claims.

Having thus described the invention, what I claim is:

1. A grade crossing gate mechanism of the character described including a swinging gate at one side of the crossing, pivoted 85 so as to tend to move to a closed position because of its own weight, means for maintaining the gate in an open position, a post on the other side of the crossing against which the end of the gate is adapted to rest 90 when closed, a rod movable longitudinally through the post for engaging the gate and means for pushing upwardly on the rod for projecting the gate to an open position, said means being actuatable by a spring. 95

2. In combination, a pivotally mounted gate fulcrumed so as to normally close under its own weight, a post for receiving the gate in its closed position, a rod slidable through the post, a lever pivoted so as to 100 provide a long and a short arm, the long arm having its end engaged with the lower end of the rod, and a slidably mounted pin for engaging the short arm so that a frame wheel may engage said pin for swinging 105 the lever, thus pushing the rods and projecting the gate to an open position.

In testimony whereof I affix my signature.

JOSEPH SCHIFTNER.
